UNITED STATES PATENT OFFICE.

VICTOR H. HARBERT, OF CHICAGO, ILLINOIS, ASSIGNOR TO E. PAYSON SMITH, OF SPRINGFIELD, ILLINOIS.

BRAKE-HANGER SUPPORT.

Application filed January 15, 1927. Serial No. 161,415.

My invention pertains to means whereby the brake hangers of railroad cars are pendently supported in place from a portion of the truck frame; the invention having for its object the provision of means adapted to the use of either the continuous link type of hanger or the U-shape type of hanger, and therefore permits an interchange of hangers.

Another object of my invention is to provide retainer elements for holding the hangers in place and of such construction that positioning of the hangers may be easily made and removal when necessary as readily accomplished; the keeper elements being adapted to receive certain of the thrusts encountered by the hangers and therefore taking care of wear resulting from the constant vibration and oscillatory movement of the hangers.

Another object of my invention is to provide a construction whereby the hangers or links will be held in proper brake-applying position for temporary use in the event of loss or misplacement of the keeper element while on the right-of-way, without permitting an improper dropping down of the hanger and therefore of the brakes.

My present invention contemplates an arm or extension preferably cast or formed integral with the truck frame and made to provide a pocket or socket to receive either the link hanger or a hanger supporting pin and my improved keeper elements; the latter, in conjunction with the pocket or socket forming portions of the arm, being such that lateral or sidewise play of the keeper elements is prevented and also endwise movement of the hanger supporting pin made impossible.

Another object of my invention is to provide a construction whereby rotation of the supporting pin when the U-shape hanger is employed, is made impossible because of an interlocking relation therewith and as a result all wear, resulting from vibratory and oscillatory movements of the hanger will be confined to the hanger and its supporting pin.

The objects and advantages of my invention will be more readily comprehended from the detailed description of the accompanying drawing, wherein—

Figure 1 is a side elevation of an arm or extension on the truck side-frame, provided with my improved means; a portion of the latter and the truck side-frame being in section, with portions of the supporting hanger broken away.

Figure 2 is a vertical sectional view taken substantially on the line 2—2 of Figure 1 looking in the direction of the arrows.

Figure 3 is a vertical sectional view taken on the line 3—3 of Figure 1 looking in the direction of the arrows.

Figure 4 is a horizontal sectional view taken substantially on the line 4—4 of Figure 1 looking in the direction of the arrows.

Figure 5 is a perspective view of one form of my improved keeper element.

Figure 6 is a view substantially similar to Figure 1 illustrating the use of the link-type of hanger and showing a modification.

Figure 7 is a view similar to Figure 1, showing a modification.

Figure 8 is a vertical sectional view taken on the line 8—8 of Figure 7.

Figure 9 is a longitudinal sectional view taken on the line 9—9 of Figure 7.

Figure 10 is a perspective view of the portion of truck frame and the integral arm shown in Figure 7.

Figure 11 is a perspective view of the keeper element employed with the construction shown in Figures 7 to 10.

Figure 12 is an elevation of a portion of the arm on the truck frame and of the construction shown in Figure 10; the figure showing the use of a continuous link hanger, only a portion whereof is shown.

My invention contemplates the use of either the U-shape type of hanger shown at 15 in Figure 1 or the link hanger shown at 16 in Figure 6; the invention involving means whereby the hanger will be securely held in place while at the same time permitting the necessary oscillatory movement thereof.

Describing the exemplification disclosed in Figures 1 to 5, we find a portion of the truck side-frame shown at 17 which, on its inner side and disposed in a direction transversely of the side-frame is provided with an arm 18 preferably integral with the frame and having a top horizontally disposed flange portion 19 which, at predetermined points in the particular exemplification in Figure 1, is preferably shown provided with the upwardly disposed arcuate portions 20, 20 arranged coincident with the vertically disposed portions of the hanger. These arcuate portions are intended to provide a suitable spacing or clearance therebeneath to receive the enlarged eyeleted ends of the U-shape link 15 when the latter is employed. The flange portion 19 is formed in

tegral with end flange portions 21, 21 which, in turn, are formed integral with the lower end flange portions 22, 22; the lower end flanges 22 being in spaced relation with an intermediate lower flange portion 23 arranged in horizontal alignment therewith. The spacing between the flanges 22, 22 and 23 is sufficient to provide a socket therebetween for the side portions of the hanger 15, or hanger 16 as the case may be, and allow the necessary oscillatory movement thereof. The lower flanges 22, 22 and 23 are shown reinforced by the lips 24 formed integral therewith and with the arm 18. That is to say, a continuous flange of comparative width and disposed laterally from the side of the arm 18 is employed, being cut away at bottom for passage of the sides of the hanger, to provide an enclosed pocket open on one side toward the wheels of 20 the truck.

The arm 18, at a point intermediate of the arcuate portions 20, 20 and adjacent to the slots or spacings in the pocket for passage of the hanger sides, is provided with the integral laterally disposed ribs 25, 25, integral with the top and bottom flange portions or pocket walls 19 and 23. The upper parts of the ribs 25, 25, connected together by the top wall or flange 19, are formed, in conjunction with the top wall or flange 19, to provide a socket 26 and shoulder 27 arranged forward of the socket, see Figure 2. The top wall 19 of the pocket, at an intermediate point, for the sake of lightness in construction, is provided with a forwardly disposed lobe or extension 28, and the lower flange portion 23 provided with a lobe or extension 29; both of which are provided with registering apertures to receive a bolt 30 whereby the retainer 40 or keeper element 31, shown in Figure 5, is locked in place; the bolt passing through an aperture 31^a in the keeper.

My improved keeper or retainer element, shown in Figure 5, comprises an elongated plate, of thickness commensurate with the vertical width of the pocket on the arm 18, with its ends 32, 32 curved or bent toward one side of the longitudinal axis of the plate and therefore arranged parallel with each other. The ends 32, 32 are preferably shown curved at 33 to provide suitable sockets adapted to receive the enlarged upper eyeleted ends of the U-shape hanger 15 when the latter is employed. The plate or keeper element 31, intermediate of its ends 32, is provided adjacent to its bottom with an upwardly curved lug or lip 34 formed to provide a longitudinal socket 35 for reception of the supporting pin 36 for the U-shape hanger 15 or the upper end of the hanger 16, see Figure 6. The keeper element is cut away or recessed at opposite ends of the lip 34 to provide the shoulder portions 37, 37, see Figure 5, which are adapted to abut against the ribs 25, see Figure 4. The ends 32 of the

keeper plate are disposed beyond the sockets between the flange portions 22 and 23 of the lower wall of the pocket, namely at the ends of the main portion of the pocket in the arm 18. These ends 32 of the keeper plate 31 are apertured at 38 in alignment with the longitudinal socket 35 formed by lip 34 to receive the supporting pin 36 of the U-shape hanger 15.

The end walls 21, either one or both, of the pocket, are shown off-set at 21^a in order to provide a small socket at either end,—or both ends,—of the pocket at a point beyond the ends of the main portion of the pocket where the ends of the keeper plate are located. The small pocket—or pockets—formed by the off-set 21^a is for the purpose of receiving the extended ends 36^a of the pin 36.

The extension or ends 36^a are non-circular in cross-section and are preferably of cross-sectional dimensions less than the diameter of the main portion of the pin 36. That is to say, in the particular exemplification a segment of the pin at the ends is cut away to provide a flat side which engages with the shoulder 39 formed by the off-set 21^a of the end walls 21 of the pocket; the socket at the end of the pocket being just sufficient to receive the reduced end. It is apparent that the pin 36, will, therefore, be held against rotation, with the result that all wear is confined to the replaceable parts of the support, namely to the more inexpensive parts, the pin and the link. It is also apparent that the reduced portion of the pin is disposed beyond the shearing point with the result that the structure is in no way weakened, but is fully capable to withstand the strains to which it is subjected.

In application, the pin 36 is inserted through the apertures 38 and through the eyeleted upper end of the hanger 15 and the pin is placed in the socket 35 of the curved lip 34 of the keeper plate. The keeper plate, with the suspended hanger, is then inserted into the pocket defined by the flange portions 19, 21, 22 and 23; the pin being positioned so that ends 36^a will enter the sockets at the ends of the pocket with the flat portions bearing against the shoulders 39.

When the keeper plate has been properly inserted into place, the shoulders 37, 37 will abut against the ribs 25, while the lip 34 will extend into the socket or space intermediate of the vertical ribs 25, see Figures 2 to 4. The keeper plate is thus properly positioned and also held against any lateral oscillatory movement. The locking bolt 30 is then inserted through the registering apertures in the pocket defining flange and the keeper plate. The supporting pin 36 of the link 15 will therefore rest in the socket 26 of the ribs 25 and in the groove or socket 35 of the lip 34 of the keeper plate.

Where the continuous link 16 is employed,

the upper end of the link is placed in the socket 35 of the lip 34 and wear resulting from oscillations and the downward thrusts will be confined to the link and to the removable keeper element or plate. It is apparent that an interchange of links may be had with my improved structure without necessitating alterations. In both constructions the keeper plate with the suspended hanger is inserted 10 edgewise into the open side of the pocket disposed toward the wheels of the truck.

With the ribs 25 extending toward the outer edge of the pocket in the arm 18, it is apparent, that in the event of loss or mis- 15 placement of the keeper plate 31, the hanger link or the supporting pin will be held in place against downward movement and dropping of the brakes below proper braking position therefore prevented, as the bolt 30 20 will maintain the hanger in the pocket or socket and on the ribs 25 until a replacement of the keeper may be made.

In Figures 7 to 12, I show a modification of my invention; Figures 7 to 9 illustrating the 25 use of the U-shape hanger with its supporting pin, while Figure 12 illustrates the use of the link hanger.

In this exemplification of the invention, a portion of the truck frame is shown at 40 30 and provided with a transversely disposed extension or arm 41 of sufficient thickness to permit being slotted longitudinally on one side to provide the elongated pocket or socket open toward the wheels of the truck, intermediate of the top and bottom bifurcations 35 42, 43. In order to stiffen and reenforce the arm I have shown it provided with the top rib 44, while the bottom is provided with the web 45 flaring toward and connected with 40 a vertical portion of the truck frame.

At points coincident with the sides of the hangers (which are of more or less standard construction), the arm is slotted transversely to a predetermined extent as at 46, 46, to permit the hangers to be pendently held in place and have the necessary oscillatory movement. In the particular exemplification, these slots 46 are also shown disposed slightly beyond the rib 44 in order to provide clearance for 50 the enlarged eyeleted ends of the U-shape hanger. The socket in the arm is also shown provided with spaced transverse walls or ribs 47, which reenforce the bifurcations; the ribs being cut away to provide supporting pin 55 or hanger receiving grooves and to maintain the same in spaced relation with the bottom bifurcation 43 in order that the keeper plate or element 48 may be introduced beneath the pin or hanger as the case may be.

60 The keeper 48 comprises an elongated plate of thickness commensurate with the spacing between the upper and lower bifurcations 42, 43, and provided with transverse slots 49, 49 adapted to register with the slots 46 of the 65 arm. One longitudinal side of the plate ad-

jacent to the bottom is extended to form the end lugs 50, 50 and the intermediate lug 51, which curve upwardly to provide a supporting pin and hanger receiving groove. The intermediate lug 51 is adapted to extend into 70 the socket intermediate of the ribs 47, thereby centering and properly positioning the keeper element. The keeper element is of length equal to the length of the pocket or socket formed on the arm; the keeper element 48 and 75 the bifurcations 42, 43 are provided with registering apertures as at 52, 53, to receive a locking pin or bolt 54, which locks the keeper element in place.

The keeper element at one or both ends is 80 provided with a small rib as at 55, partially closing the ends of the pin receiving groove; while the upper bifurcation 42 on the arm, at least at one end, is provided with a flat sided lip 56, which is adapted to be in alignment 85 with the rib 55 of the keeper element when the latter is in place; the lip 56 also partially extending across the end of the pocket or socket so as to leave a space between lip 56 and the 90 rib 55, as shown in Figures 7 and 8.

The U-shape hanger supporting pin 57 beyond the shearing point, namely beyond its bearing in the grooved end lug 50 of the keeper element, is provided with a flat-sided extension 58 (see Figure 7) which is adapted 95 to fit into the space between the lip 56 and the rib 55 and as a result will hold the pin against rotation.

With this construction, like in the previously described structure, all wear will be confined to the pin, and the integral portions of the truck frame or of the arm and the more expensive keeper plate will be free of any wear. A serious objection to hanger mountings as heretofore employed is therefore entirely eliminated, while at the same time permitting an interchanging of the hangers, themselves, as is apparent from Figure 12, where the link type of hanger 16 is shown substituted for the U-shape hanger 15 and its supporting pin 57; the structure in Figure 12 being in every other respect similar to that shown in Figure 7.

It is apparent that the rib 55 and the lip 56, like the shoulder 39 in the construction shown in Figure 1, will hold the pin against longitudinal movement also.

Instead of off-setting the end walls of the pocket or socket as shown in Figure 1 to provide a pin engaging shoulder 39, the end walls 21 of the pocket or socket in the projection or arm 18 may be entirely vertical as shown in Figure 6 and one or both end walls 21 provided with a slot 59 of vertical depth just sufficient to receive semi-circular extended ends 36^a of the pin 36 when the U-shape hanger 15 is employed. Figure 6 shows the application of a continuous link hanger 16 instead of the U-shape hanger 15 and its supporting pin 36 which is shown in Figures 1 and 4.

My improved structures involve a keeper element for supporting the hanger pin or the hanger in place and to take the down thrusts and wear when the link hanger is used thereby relieving the integral portion of the truck frame, as well as means for holding the hanger pin against rotation when the U-shape hanger is used; and while I have shown specific exemplifications of such structures, certain alterations in details may be made without, however, departing from the spirit of my invention.

What I claim is:

1. A brake hanger support comprising, the combination of a truck frame provided with an inwardly projecting arm having a vertically disposed face with a laterally extending elongated pocket open toward the wheels of the truck and slotted transversely for passage of the hanger, forwardly extending ribs in the pocket terminating at the front edge thereof and cut away to provide an arcuate groove, with a plate insertible in said pocket, the ends of the plate being formed to receive the ends of a hanger supporting pin, while the intermediate portion of the plate adjacent to the bottom is provided with an upwardly curved lip adapted to seat between the ribs in said pocket.
2. In a brake hanger support, a truck frame provided with a transversely disposed arm having an elongated pocket disposed toward the wheels of the truck, a pair of spaced ribs in said pocket formed to receive a link and a link supporting pin, and a plate insertible in said pocket, the ends of the plate being formed to seat the ends of the pin while the intermediate part of the plate has a grooved lip adapted to extend between the ribs in said pocket.
3. In a brake hanger support, a truck frame having a transversely disposed arm provided with an elongated pocket open toward the wheels of the truck, a pair of spaced ribs in said pocket spaced from the ends thereof and formed to provide a hanger and a hanger supporting pin receiving groove, a plate insertible in said pocket, the ends of the plate being formed to receive and support the ends of a hanger supporting pin while the intermediate portion of the plate has a channeled lip adapted to extend between the ribs in said pocket, and means disposed through the forward walls of the pocket for removably holding the plate in place.
4. In a brake hanger support, a truck frame provided with an inwardly extending arm formed to provide an elongated socket open toward the wheels of the truck, the socket being provided with a transversely disposed portion cut away to provide a hanger and a hanger-pin receiving groove, a thrust receiving element insertible in said pocket and provided with a groove adapted to register with the groove of said integral portion,

said element and the forward part of the pocket being transversely slotted for passage of the hanger, and locking means secured to the walls of the pocket.

5. In a brake hanger support, the combination of a truck frame provided with an inwardly extending arm, the vertical side whereof is formed to provide an elongated horizontal pocket, a pair of transversely disposed spaced ribs in the pocket formed to receive a hanger and hanger supporting pin, with a plate insertible in said pocket, the ends of the plate being disposed parallel with the ends of the pocket and apertured while the intermediate part of the plate has a channeled lip adapted to extend between the ribs in said pocket, and means disposed through the walls of the pocket and said plate for locking the plate and the hanger in place.

6. In a brake hanger mounting, an arm secured to a truck frame and formed to provide a laterally disposed pocket opening toward the wheels of the truck, a keeper element insertible laterally into said pocket, said element being transversely socketed to receive the sides of the brake hanger while the ends of the element are apertured, a hanger supporting pin extending lengthwise of the keeper element with the ends of the pin disposed through the apertured ends of the keeper element, with the ends of the pin having non-rotating relation with the wall of said pocket.

7. In a brake hanger support, an arm on the truck frame formed to provide a laterally disposed socket open toward the wheels of the truck, a hanger supporting pin, the pin and arm being provided with correlated surfaces whereby rotation of the pin is prevented, and means for locking the pin in place.

8. A brake hanger support comprising an arm on the truck frame provided with a laterally disposed socket open toward the wheels of the truck, a keeper plate insertible laterally into the socket and having apertured ends, a hanger supporting pin insertible through the apertured ends of the keeper plate and provided with extensions beyond the shearing points on the pin, said extensions and the ends of the socket having non-circular contacting surfaces whereby rotation of the pin is prevented, and means for locking the keeper plate in said socket.

9. A brake hanger support comprising an extension on the truck frame formed to provide a socket open toward the wheels of the truck, a hanger supporting pin insertible in said socket and having a non-circular portion adapted to abut against a transverse wall of the socket whereby rotation of the pin is prevented, and means for locking the pin in place.

10. A brake hanger support comprising an arm on the truck frame provided with a socket, a brake hanger, a supporting pin for

70

said hanger and seatable in said socket, a keeper element grooved to receive the pin and insertible in said socket, the arm beyond the shearing point on the pin and the pin being provided with non-circular engaging surfaces whereby rotation of the pin is prevented.

11. A brake hanger support comprising an arm on the truck frame provided with an elongated socket open toward the wheels of the truck, the arm at the end of the socket having a flat faced lip, a brake hanger supporting pin insertible in said socket and provided with a flat-sided end adapted to engage with said flat faced lip, and a keeper element 15 grooved longitudinally to receive said pin and insertible into said socket, the end of the groove in said element being partially closed by a rib adapted to engage the opposite flat side of said pin.

12. A brake hanger support comprising an arm on the truck frame having a laterally disposed socket open toward the wheels of the truck and adapted to receive a brake hanger and a hanger supporting pin, means 25 insertible edgewise into said socket for locking the brake hanger and hanger supporting pin in place, and means whereby rotation of the hanger supporting pin is prevented.

13. A brake hanger support comprising an arm on the truck frame having a laterally disposed socket open at the wheels of the truck, the lower wall of the socket being transversely slotted for passage of the sides of the brake hanger, said socket being adapted to receive 35 the end of a brake hanger and a brake hanger supporting pin, the ends of the socket being formed to prevent longitudinal movement and rotative movement of the supporting pin.

14. A brake hanger support, comprising an

arm on the truck frame provided with a laterally disposed socket open toward the wheel of the truck, the bottom wall of the socket being transversely slotted for passage of the sides of the brake hanger, the socket being formed to receive the end of a hanger and to receive a hanger supporting pin, the end of the socket being provided with a flat sided shoulder, a supporting pin having a flat sided extended end beyond the shearing points on the pin, the flat sided extension of the pin being adapted to have interengaging relation with the flat sided shoulder at the end of the socket, and means for locking the hanger and the hanger supporting pin in said socket.

15. In a brake hanger support, a keeper element formed to provide a hanger pin receiving channel disposed lengthwise of the element, the element adjacent to the ends being slotted transversely of the channel to receive the sides of the hanger, while the ends of the element are apertured, a hanger pin insertible in said channel and in said apertures, and means beyond the shearing point at the end of the pin whereby rotation of the pin in the element is prevented.

16. In a brake hanger support, a keeper element formed to provide a hanger supporting pin receiving channel, the element adjacent to the ends being slotted transversely to receive the sides of the hanger, and a hanger supporting pin, an end of the pin and end of the element being provided with non-circular extensions beyond the bearing point of the pin and having matching faces whereby rotation of the pin in the channel is prevented.

VICTOR H. HARBERT.
